(57) **CLAIM**

The ornamental design for the buckle assembly, as shown and described.

DESCRIPTION

FIG. 1 is an isometric view of an embodiment of a buckle assembly showing our new design.

FIG. 2 is a top plan view thereof.

FIG. 3 is a bottom plan view thereof.

FIG. 4 is a left side elevation view thereof.

FIG. 5 is a right side elevation view thereof.

FIG. 6 is a front elevation view thereof.

FIG. 7 is a back elevation view thereof.

FIG. 8 is an isometric view of a second embodiment of a buckle assembly showing our new design.

FIG. 9 is a top plan view thereof.

FIG. 10 is a bottom plan view thereof.

FIG. 11 is a left side elevation view thereof.

FIG. 12 is a right side elevation view thereof.

FIG. 13 is a front elevation view thereof; and,

FIG. 14 is a back elevation view thereof.

Elements identified in broken lines in the accompanying drawings form no part of the claimed invention.
